[57] CLAIM

The ornamental design for a flexible towel holder, as shown and described.

DESCRIPTION

FIG. 1 is a perspective view of a flexible towel holder, showing my new design;

FIG. 2 is a top plan view thereof;

FIG. 3 is a side elevation thereof, the opposite side being a mirror image of that shown;

FIG. 4 is a bottom plan view thereof;

FIG. 5 is an end elevation view thereof;

FIG. 6 is an opposite end elevation view thereof;

FIG. 7 is a side elevation view thereof shown in operating position; and,

FIG. 8 is a front perspective view thereof, the broken line showing of the lawn chair and cover is for illustrative purposes only and forms no part of the claimed design.
